United States Patent Office

Des. 185,313
Patented May 26, 1959

185,313

COMBINED THERMOMETER AND MEMORANDUM PAD HOLDER

James R. Reichow, St. Paul, Minn., assignor to Brown & Bigelow, St. Paul, Minn.

Application September 9, 1957, Serial No. 47,651

Term of patent 14 years

(Cl. D74—1)

FIG. 1

FIG. 2

FIG. 3

FIG. 4

Fig. 1 is a front perspective view of a combined thermometer and memorandum pad holder showing my new design;

Fig. 2 is a side elevational view thereof;

Fig. 3 is a front elevational view; and

Fig. 4 is a top plan view thereof.

The broken line illustration of a pad is for illustrative purposes only.

I claim:

The ornamental design for a combined thermometer and memorandum pad holder, as shown and described.
